UNITED STATES PATENT OFFICE.

JESSE E. McGEE, OF GUNTOWN, MISSISSIPPI.

SERVING-TRAY SUPPORT FOR AUTOMOBILES.

Application filed January 17, 1924. Serial No. 686,851.

To all whom it may concern:

Be it known that I, JESSE E. McGEE, citizen of the United States, residing at Guntown, in the county of Lee and State of Mississippi, have invented certain new and useful Improvements in Serving-Tray Supports for Automobiles; and I do hereby declare the following to be a full, clear, and exact description of the invention, such as will enable others skilled in the art to which it appertains to make and use the same.

This invention relates to an improved construction of serving tray support for automobiles, and more particularly to a support which will be readily clamped to or over the top of a door of an automobile to support a tray, when refreshments are to be served at the curb or at any other time.

An object of the invention is to provide a suitable serving tray support for automobiles which will adapt itself to fit on different sizes of automobile doors, or other parts of an automobile to support a tray when refreshments are being served at the curb, thereby making it unnecessary for the occupants of the automobile to leave the same.

A further object of the invention is to provide a serving tray support for automobiles which will be highly efficient in use, and quite inexpensive to manufacture.

Other objects will appear as the description proceeds.

In the accompanying drawings which form a part of my application,

Figure 1 is a side elevation of my improved serving tray support, showing a door positioned thereon.

Figure 2 is a vertical sectional view taken on the line 2—2 of Figure 1, with the tray removed from the support, and,

Figure 3 is a transverse sectional view taken on the line 3—3 of Figure 2.

Like characters of reference will be used throughout the specification and the accompanying drawings to designate corresponding parts.

My invention comprises a skeleton body portion, which is provided with spaced laterally extending arms 1 and arms 2 at the opposite ends of the said body portion. All of the arms 1 and 2 are inclined upwardly and are adapted to receive the cushioning bands 3, which are securely held in place by the bent over ends 4 of the said arms. The cushioning bands 3 are preferably

formed of a rubber composition, although they may be formed with any desired material, and are arranged so that new bands may be placed on the arms when desired.

A bracket 5 is secured to the underneath surface of the body portion adjacent one end thereof, and extends downwardly and connected at its lower end to a fixed handle 6. A bearing rod 7 is secured to the bracket 5 and extends approximately the whole length of the body portion of the support, and in spaced relation thereto. The opposite end of the bearing rod 7 is bent upwardly and is fixedly attached to the said body portion. An inverted U-shaped slide member or clamping member 8 is provided with the downwardly extending clamping arm 9, on which is positioned the cushioning band 10, and a downwardly extending arm 11 to which is attached the movable handle 12. This slide member is provided with alined openings which are of such a size as to snugly engage the bearing rod 7, in such a manner that the upper portion of the slide member 8 will slidably contact on the underneath surface of the body portion of the support. A suitable stop 13 is attached to the underneath surface of the body portion and is adapted to limit the movement of the slide member. A coil spring 14 is positioned about the bearing rod 7 and passes through an opening 15 therethrough and has its opposite end connected with the downwardly extending clamping arm 9 so that the said clamping arm will normally be drawn away from the fixed handle 6.

Spaced downwardly extending clamping arms 16 are attached to the underneath surface of the body portion of the support and extend at opposite sides of the bearing rod 7. The clamping arms 16 are also provided with the cushioning bands 17. Each of the arms 16 is provided with the horizontally disposed rods or arms 18 on which are positioned the cushioning bands 19, it being understood that the arms 18 extend in the same plane with the bearing rod 7.

The body portion is so shaped that it readily supports a tray 20 in an efficient manner so that the same may be moved from place to place without danger of overturning the refreshments carried by the tray.

It is often the case that persons in an automobile will drive up to a store and request that refreshments be served at the

curb, and my present invention is provided so that a waiter will grasp the fixed and movable handles 6 and 12 in such a manner that his thumb will engage the fixed handle 5 and several of his fingers will engage the movable handle. Assuming that the tray was upon the support and the refreshments were on the tray, the waiter upon arriving at the automobile draws the movable handle 10 towards the fixed handle against the tension of the spring 14 thereby providing a further space between the fixed downwardly extending clamping arms 16 and the movable clamping arm 9, until the space is 15 sufficient to position the fixed clamping arms on the inside of the automobile door and the movable clamping arm on the outside thereof, whereupon the tension of the spring 14 will support the tray supporting means 20 in place. The rods or arms 18 will engage the top surface of the door thereby holding the tray supporting means in fixed position. It will then be quite simple to serve the occupants of the automobile or the 25 occupants to serve themselves, and when they have finished their repast they may again place the glasses or dishes on the tray and not have to hold the same until the waiter again comes out to the automobile.

30 Many minor changes in detail of construction may be resorted to without departure from the spirit of the invention.

Having thus described my invention what I claim as new and desire to secure by 35 Letters Patent of the United States is:—

1. A serving tray support for automobiles comprising a body portion provided with outwardly and upwardly extending tray supporting arms, a handle fixed to the under surface of said body portion, a bearing 40 rod secured to said handle at one end and at its opposite end to the body portion, and in spaced relation thereto, fixed clamping arms carried by said body portion, a slide- 45 able clamping arm mounted on said bearing rod, a second handle connected with said slideable clamping arm adapted to draw the same away from said fixed arms, and resilient means normally tending to draw said 50 slideable clamping arm toward said fixed clamping arms.

2. A combination as set forth in claim 1, and cushioning means on all of said arms.

3. A serving tray support comprising a

body portion, a handle fixed to the under surface thereof, a bearing rod secured to said handle at one end and at its opposite end to the said body portion and in spaced relation thereto, fixed clamping arms carried by said body portion, a slideable clamping arm mounted on said bearing rod, a second handle connected with said slideable clamping arm adapted to draw the same away from said fixed arms, resilient means 60 normally tending to draw said slideable clamping arm towards said fixed clamping arm, cushioning means on all of said arms, and a stop positioned on the underneath surface of said body portion adapted to 65 limit the movement of said slideable clamping arm.

4. The combination with a serving tray, of a longitudinally extending rod arranged below the tray and having one end fixed 75 thereto, a handle carried by the opposite end of tray to which the opposite end of the rod is attached, fixed clamping members carried by the tray and adapted to engage one face of a vertical support, an inverted 80 U shaped member having its legs slidably mounted on the rod and one leg being disposed in opposed relation to the fixed clamping members and constituting a movable clamping member to engage the opposite 85 face of the vertical support, the other leg constituting a handle which lies parallel to the first mentioned handle and a resilient element normally urging the inverted U shaped member towards the fixed clamping 90 member.

5. A device of the character described, comprising a body, a rod carried thereby and extending parallel thereto, a fixed handle carried by one end of the body, a plurality 95 of clamping members carried by the body and extending at right angles thereto and adapted to engage one face of a support arranged at right angles to the body, an inverted U shaped member slidably mounted on the rod and one leg serving as a clamping member to engage the opposite face of such support, the other leg constituting a handle which extends parallel to the fixed handle, and resilient means normally 100 urging the inverted U shaped member toward the fixed clamping members.

In testimony whereof I affix my signature.

JESSE E. McGEE.
